Fig. 2.

Fig. 3.

Fig. 4.

FIG. 1 is a plan view of the front face of a wall panel incorporating the dominant features of the design of this invention, the features being superimposed upon a field of regularly shaped perforation;

FIG. 2 is a fragmentary sectional view taken on line 2—2 of FIG. 1;

FIG. 3 is a plan view of a panel similar to that illustrated in FIG. 1, but without the field of regularly shaped perforations; and

FIG. 4 is a plan view of a panel similar to that illustrated in FIG. 1, but with a more open over-all pattern.

The dominant features of my design reside in the over-all pattern of a non-directionalized arrangement of irregularly shaped cavities in the face of a wall panel.

I claim:

The ornamental design for a wall panel, as shown and described.
